UNITED STATES PATENT OFFICE.

HYRUM PETERSON, OF HOOPER, UTAH.

FENCE-POST AND FENCE-WIRE FASTENER.

987,485.

Specification of Letters Patent. Patented Mar. 21, 1911.

Application filed March 6, 1909. Serial No. 481,568.

To all whom it may concern:

Be it known that I, HYRUM PETERSON, a citizen of the United States, residing at Hooper, in the county of Weber, State of Utah, have invented certain new and useful Improvements in Fence-Posts and Fence-Wire Fasteners; and I do hereby declare the following to be a full, clear, and exact description of the invention, such as will enable others skilled in the art to which it appertains to make and use the same.

This invention relates to fences, more particularly to posts of fences and the fasteners for the strand wires thereof, and has for one of its objects to improve the construction and increase the efficiency and utility of devices of this character.

With this and other objects in view, the invention consists in certain novel features of construction as hereafter shown and described and then specifically pointed out in the claims, and in the drawings illustrative of the preferred embodiment of the invention, Figure 1 is a side elevation of a fence post together with a plurality of the improved wire fastening means applied. Fig. 2 is a sectional detail enlarged on the line 2—2 of Fig. 1. Fig. 3 is a transverse section enlarged on the line 3—3 of Fig. 2. Fig. 4 is a view of one of the wire fastening devices detached and in the form that it will appear before being applied.

The improved device comprises a post 10, preferably tubular and of metal. The post 35 is preferably formed from a section of metal tubing, and may be of any required size, and will preferably be galvanized or otherwise coated or protected to prevent corrosion. The post 10 is provided with a plurality 40 of spaced apertures 11 extending in a line longitudinally of the post, the apertures being so arranged that they are employed in pairs to correspond to the strand wires represented at 12 as hereinafter explained. 45 The apertures are formed with their sides converging inwardly as shown in Figs. 2 and 3.

The fastening devices are in the form of staples 13 one of which is represented in Fig. 4, and when ready to be applied to the post and bent into U shape with the sides in parallel relations. The inner faces of the sides of the staples 13 are reversely inclined as shown at 14—15 and with notches 55 16—17 at the inner terminals of the inclined faces, as shown. To apply the staple the

wire 12 is arranged across the post in the ordinary manner and the staple located over the wire with the inclined faces 14—15 within two of the apertures 11, and force applied to the outer or right portion of the staple with the result of causing the sides of the staple to be distended and pass through the apertures until the notches 16—17 engage over the inner edges of the apertures, 60 the resiliency of the staple then causing the sides to firmly grip the material of the post between the apertures as shown in Fig. 2, and thus lock the strand wires to the posts. These apertures are preferably 70 frusto-conical in form and are evenly spaced so that the staple may be inserted between any two adjacent apertures.

The improved device is simple in construction, can be inexpensively manufactured, and applied, and effectually holds the strand wires in position upon the post.

What is claimed, is:

1. The combination with a tubular fence post having a plurality of spaced frusto-conical apertures having their enlarged ends facing outward, of wire supporting devices for said apertures, and each comprising a wire bent U-shaped with the inner faces of the side members thereof inclined at their 80 free ends and with notches at the terminals of the inclined portions, said side members being inserted through said apertures until the notches engage over the inner edges of the apertures, whereby the supporting devices are adapted to support a strand wire 85 against the post.

2. The combination with a tubular fence post provided with a plurality of frusto-conical apertures spaced apart, of strand 95 wires extending transversely of said post, and fastening devices each formed of resilient wire bent into U-shape with the side members normally in parallel relations, the confronting faces of said side members being provided with notches and the inner faces inclined at the free ends, the apertures of the post being spaced apart a greater distance than the normal space between the sides of the fastening devices. 100

3. The combination with a tubular fence post provided with a plurality of evenly spaced frusto-conical apertures, said apertures having their large ends facing outward; of a wire fastening device comprising 110 a length of resilient wire bent to U-shape, the arms of the U being adapted for inser-

tion in any two adjacent apertures, said arms being further provided with notches adapted to engage the inner edges of said adjacent apertures to releasably prevent detachment of the fastening device from the post and being releasable therefrom by springing apart with a suitable tool.

In testimony whereof, I affix my signature, in presence of two witnesses.

HYRUM PETERSON.
